UNITED STATES PATENT OFFICE.

LE ROY DODD SPENCER, OF WINESAP, WASHINGTON.

SORTING OR SIZING APPARATUS.

Application filed March 24, 1922. Serial No. 546,439.

To all whom it may concern:

Be it known that I, LE ROY DODD SPENCER, a citizen of the United States, and a resident of Winesap, in the county of Chelan and State of Washington, have invented certain new and useful Improvements in Sorting or Sizing Apparatus, of which the following is a specification.

This invention relates to a sorting or sizing apparatus.

The object of the invention is to provide an apparatus of the above character by which apples or the like may be sorted or graded into different sizes in a highly efficient and expeditious manner.

It is also an object of the invention that the apparatus be adapted to grade or sort objects such as apples or the like into any number of sizes desired.

It is further an important object of the invention that the apparatus be extremely simple in construction and inexpensive to manufacture.

It is a still further object of the invention that means be provided whereby in sorting the apples or the like the same will not be bruised.

Other objects and objects relating to details of construction, combination and arrangement of parts will hereinafter appear in the detailed description to follow.

The invention is illustrated by way of example in the accompanying drawings in which,

Figure 1 is a perspective view illustrating a sorting or grading apparatus constructed in accordance with the present invention.

Figure 2 is a vertical transverse sectional view of the same.

Figure 3 is a top plan view of a modified form of the invention.

Referring to the drawings more particularly Figure 1 indicates generally a bin which is preferably of the shape shown and supported by the legs 10. The bin comprises the end walls 11, side walls 12 and the two top walls 13, said top walls extending longitudinally of the bin and their adjacent sides being spaced from each other. Also the legs 10 are braced by longitudinals 15 and the two end members 16.

The interior of the bin B is divided into a plurality of compartments generally indicated by the reference character C, said compartments being formed by the vertical division walls 17, and said walls extending

transversely of the bin and arranged in longitudinal spaced relation of the same.

At one end of the bin there is secured to the end wall 11 suitable brackets as at 18 between which there is mounted a roller 19. Also there is supported by the brackets the one end of a hopper generally indicated by the reference character H, said hopper comprising an inclined bottom 20 and the retaining boards 21 which are three in number and the end retaining board being recessed as at 22 and having brackets 23 extending therefrom between which there is rotatably supported a roller 24. About the rollers 19 and 24 there extends a plurality of belts 25, said belts being preferably two in number as shown and the lower section of each belt passing beneath the bottom of the hopper H while the upper section thereof operates immediately over the upper surface of the hopper bottom 20. The purpose of this will later appear.

From the other end of the bin B there extends a pair of brackets 26 between which there is rotatably supported a roller 27 and said brackets being secured together by a cross member 28. The roller on its one end carries a pulley 29 about which may pass a power belt 30. About the rollers 19 and 27 there extends two outer belts 31 and an intermediate belt 32. Each of the belts 31 gradually diverges from the belt 32 from the roller 19 toward the roller 27. As shown in Figure 2 there is extended longitudinally of the bin for each belt a supporting member 33 and a like supporting member 34 for the belt 32. Upon each supporting member 33 there is laid a guide rail or the like as at 35 and a similar rail 36 is positioned upon the support 34 for the belt 32. In each instance the belts 31 have their outer edge provided with a retaining flange 37 which extends upwardly as shown and also each guide rail 35 is recessed as at 38 for receiving the associated belt 31. To each guide rail 35 there is secured a retaining plate member 39 which is recessed longitudinally as at 40 to receive the retaining flange 37 of the associated belt 31. It also may be mentioned that the inner edges of the guide rails 35 and likewise the supporting members 33 are inclined as shown in Figure 2 and also the edges of the supporting plate 34 and guide rail 36 are sloped inwardly as likewise shown.

Each guide rail 35 and its associated re-

taining plate member 39 are pivotally secured to the bin B by means of a bolt as at 41, said bolt in each instance being adapted to permit the guide rail 35 and associated plate member 39 to swing longitudinally and therefore permit the opposite ends thereof to be used for adjusting the distance between belt 32 and belts 31.

At the free ends of the guide rails 35 and plate members 39 there is positioned for each guide rail an L-shaped clip 42 which has extended through its free end an adjustable bolt 43 which may be used for adjustably holding the associated guide rails 35 and its retaining plate 39.

The belt 32 is also provided with a rib 44 which extends centrally and longitudinally thereof and from the cross member 28 between the bracket members 26 there is extended rearwardly a guide member 44 which is provided with a suitable slot extending longitudinally thereof and in its lower face adapted for receiving the rib 44 of the belt 32 and thus serving as a guide means for said belt and retaining the same in a central position with respect to the rollers 19 and 27.

Each compartment C is provided with a pair of compressible bottoms 45 (Figure 2). Each bottom is hinged at its inner end as at 45' to the longitudinal division wall 44', and the outer end of each bottom is supported by compression springs 46. Preferably two compression springs are associated with each bottom, and said compression springs are supported by the longitudinals 15 extending between the legs 10.

In the use of the present device apples or other objects to be sorted or sized are deposited in the hopper H and then the power is supplied from the belt 30 for rotating the rollers 19, 27 and 24. The belts 31 and 32 should move so that their upper sections will travel in a direction from the hopper H and the upper sections of the belts 25 should move in a similar direction. With this occurring the apples will be taken from the hopper H and deposited in the slots occurring between the opposing edges of the belts 31 and 32. The apples or objects being sorted will pass along and sized or sorted, the different sizes dropping into the compartments C there-beneath.

If it is desired to more closely sort apples or the like, then of course, the screws 43 should be adjusted for properly spacing the belts 31 and 32.

The springs 46 are adapted to hold the floor 45 so that when no objects are deposited in a compartment the bottoms 45' are substantially horizontal. As the compartments fill, the outer ends of the bottoms are depressed. As is apparent the apples will at all times drop the same distance, and

since the distance is not great no bruising of the apples will occur. In Figure 2 the bottoms 45' are shown as depressed viz., the different compartments have been filled, the dotted line indicating the top surface 70 of apples or other objects in these compartments.

Referring to Figure 3, B' indicates a bin which is longitudinally divided into compartments C'. The one end of the bin is secured to the hopper H' which supports the rollers 19' and 24'. The bin B' is of greater length than the bin shown in Figures 1 and 2, and additional compartments C' are provided. This for the purpose of 80 grading the apples or other objects into a greater number of sizes. At the end opposite to the hopper H' of the bin B' there is positioned a roller 27' and intermediate the roller 19' and 27' there is supported a roller 9. Over the rollers 19' and 24' there passes the three belts 25' which are adapted to move the fruit from the hopper H' upon the sizing apparatus. Over the rollers 9 and 19' there passes the two outer belts 31' and about the rollers 21' and 19' there passes the two intermediate belts 32'. The belts 32' diverge from each other as shown, and each belt 31' in turn diverges from the adjacent belt 32'. The belts 32' are adapted to carry the fruit over the extended end of the hopper B' and deposit the same into compartments C'. Suitable guides and adjusting means for the different belts are provided in this instance, the same as with the apparatus shown in Figures 1 and 2 and will not be described in detail. The different belts are driven by a power belt 30'.

In the operation of the modified form of invention shown in Figure 3, the apples or other objects are taken from the hopper H' by the belts 25' and moved upon the different belts 31' and 32'. The smaller apples are of course dropped into the first compartments C' between each of the belts 31 and adjacent belt 32; the larger apples are carried on into the furthermost compartments C' and thus providing means by which a closer grading or sizing of apples or other fruit may be had. The roller 9 should be recessed as shown at a point between the belts 32' so that apples may freely pass thereover.

While I have shown and described two forms of sizing and sorting apparatus embodying my invention, it is to be understood that I am aware of the fact that various changes and modifications may be made herein without departing from the spirit of the invention or the spirit of the appended claims.

What I claim is:

1. In a sizing apparatus, a compartment, means for dropping objects being sized into the one end of said compartment, a bottom

for said compartment, and means for supporting said bottom so that the outer end thereof may be depressed with the filling of said compartment while the inner end thereof remains stationary.

2. In a sizing apparatus, a plurality of compartments into which the objects being sized may be distributed, and a bottom for each of said compartments having its one side hinged and its other side yieldably supported.

3. In a sizing apparatus, a plurality of compartments into which the objects being sized may be distributed, and a bottom for each compartment having its inner end hinged and its outer end yieldably supported.

4. In a sizing apparatus, a plurality of compartments into which the objects being sized may be distributed, and a bottom for each compartment having its inner end hinged and its outer end supported by springs.

5. An apparatus of the character described, comprising a bin having a plurality of compartments arranged longitudinally thereof, a roller in each end of the bin and

a roller at a point intermediate the ends of the bin, a pair of belts passing about the end rollers, and a pair of belts passing about one end roller and the intermediate roller, the first named belts being disposed between the last named belts.

6. An apparatus of the character described, comprising a bin having a plurality of compartments arranged longitudinally thereof, a roller in each end of the bin and a roller at a point intermediate the ends of the bin, a pair of belts passing about the end rollers, a pair of belts passing about one end roller and the intermediate roller, the first named belts being disposed between the last named belts, and a guide member positioned along the outer edge of each belt extending between an end roller and the intermediate roller.

7. In a device of the character described, movable belts adapted to size objects placed thereon and deliver the same to different points, a hopper, and a plurality of belts extending longitudinally of said hopper adapted to deliver objects within the hopper to the first named belts.

LE ROY DODD SPENCER.
